CLAIM

The ornamental design for a jar, as shown and described.

DESCRIPTION

FIG. 1 is a front elevation view of a jar, with the rear elevation, right side elevation and left side elevation being identical, showing my new design;

FIG. 2 is a top plan view thereof;

FIG. 3 is a bottom plan view thereof;

FIG. 4 is a top perspective view thereof; and,

FIG. 5 is a top perspective view of the jar closed with a lid shown in broken lines.

The broken lines showing a lid in FIG. 5 illustrate environmental structure. All other broken lines illustrate portions of the jar. The broken lines form no part of the claimed design.
